(57) **CLAIM**

The ornamental design for a combination travel blanket, pillow, and case, as shown and described.

DESCRIPTION

FIG. 1 is a front perspective view of a combination travel blanket, pillow, and case, showing my new design, the travel blanket and pillow contained within the case and a compression zipper closed, the case being in a compressed configuration;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top plan view of FIG. 1;

FIG. 7 is a bottom plan view of FIG. 1;

FIG. 8 is a front perspective view thereof, the compression zipper open and the case being in an expanded configuration;

FIG. 9 is a rear perspective view of FIG. 8;

FIG. 10 is an exploded perspective view thereof, illustrated in an unpackaged configuration with the travel blanket and pillow removed from the case, the broken away lines for illustrative purposes showing only what is claimed of the blanket;

FIG. 11 is an exploded top plan view of FIG. 8;

FIG. 12 is an exploded bottom plan view of FIG. 8;

FIG. 13 is an exploded left-side elevational view of FIG. 8;

FIG. 14 is an exploded right-side elevational view of FIG. 8;

FIG. 15 is an exploded front elevational view of FIG. 8; and,

FIG. 16 is an exploded rear elevational view of FIG. 8.

The broken lines in the figures depict stitching, and the square broken lines in the figures represent a zipper, both forming part of the claimed design.

The combination travel blanket, pillow, and case is shown with a symbolic break in its length. The appearance of any portion of the article between the break lines forms no part of the claimed design.
